CLAIM

The ornamental design for a shrimp display boat, as shown and described.

DESCRIPTION

FIG. 1 is a perspective view from the front, left side and above, of a first embodiment of a shrimp display boat showing our new design;

FIG. 2 is a top plan view thereof;

FIG. 3 is a right side elevational view thereof (the left side being a mirror image thereof);

FIG. 4 is a bottom plan view thereof;

FIG. 5 is a perspective view from the front, left side and above, of a second embodiment of a shrimp display boat showing our new design;

FIG. 6 is a top plan view thereof;

FIG. 7 is a right side elevational view thereof (the left side being a mirror image thereof); and,

FIG. 8 is a bottom plan view thereof.
